ANGELO PERRI, OF WATERTOWN, MASSACHUSETTS, ASSIGNOR TO REECE SHOE MACHINERY COMPANY, OF BOSTON, MASSACHUSETTS, A CORPORATION OF MAINE.

SHOE-HEEL-PREPARED MACHINE.

1,405,800.

Specification of Letters Patent.

Patented Feb. 7, 1922.

Application filed November 11, 1918. Serial No. 262,104.

To all whom it may concern:

Be it known that I, ANGELO PERRI, a citizen of the United States, residing at Watertown, in the county of Middlesex and State 5 of Massachusetts, have invented certain new and useful Improvements in Shoe-Heel-Preparing Machines, of which the following is a specification, reference being had therein to the accompanying drawing.

10 This invention is a novel shoe heel preparing machine. The main object is to provide a satisfactory machine for performing part or all of the preparatory steps between the assembling of the lifts and the actual 15 attachment to the shoe, for example, the steps of compressing, piercing, loading and nail-driving. Another object is to provide for a diverging arrangement of nails, and in connection therewith a straightening into 20 parallelism of the outstanding nail tops before the top lift is applied. Other advantages will be made clear in the following description of an illustrative embodiment.

To the attainment of such objects and advantages the present invention consists in the novel machine, combinations, arrangements, mechanisms, devices and details hereinafter explained, described, illustrated or claimed.

30 In the accompanying drawings, Fig. 1 is a left elevation of a nailing machine adapted for preparing a heel for attachment to a shoe, and embodying the present invention.

Fig. 1^a is a similar left elevation of certain parts not fully shown in Fig. 1.

Fig. 2 is a front elevation of the same.

Fig. 3 is an enlarged left elevation of the revolving heel support. Fig. 4 is a partial plan view showing part of the piercing 40 mechanism seen in the direction of the arrow 4 of Fig. 1. Fig. 5 is a rear elevation of the parts shown in Fig. 4.

Fig. 6 is a front elevation partly in section of the nail inserting and driving mechanism. Fig. 7 is a top plan view of the parts shown in Fig. 6. Fig. 8 is a plan view of the parts shown in the lower portion of Fig. 6. Fig. 9 is an elevation showing the heel, the nail guide and the nails 50 after the latter are driven nearly through the heel. Fig. 10 in similar view shows the same parts with the nails bent straight after the removal of the guide.

Fig. 11 is a perspective view of the nail 55 guide.

In Patent No. 1,289,054, Dec. 24, 1918, and likewise in the present application is shown a shoe heelng method comprising driving a series or group of nails divergently into the heel, and leaving the converging nail 60 tops outstanding slightly, and bending them into substantial parallelism before forcing a top lift into place upon said nail tops. In the particular illustration in said prior patent, the straightening of the nail tops into 65 parallelism is performed subsequently to the attachment of the heel to the shoe. In this respect the present invention is an improvement in that the bending is performed before the heel is applied, and this enables 70 certain operation which are of additional advantage. The present invention is of broad utility, and its features, or some of them, are advantageous with either described method or other methods of procedure.

To recite generally the steps performed by the present machine, each heel, after being properly compressed and shaped, is 75 preferably first pierced by a series of awls 80 to form a series of tapering holes in proper position to receive the nails. Then, unlike said prior patent, I prefer to place against the heel and between the pierced holes a tapering guide or cone which is to guide the 85 nails as they are driven. Preferably, the 90 nails are not engaged with the tapering guide until after the latter is in engagement with the heel. Next, the nails are driven into the heel nearly to the point of emerging 95 at the base. At this point I spread or straighten up the nails by bending into parallelism. This is enabled to be readily done by simply drawing or lifting off the tapering guide or cone, the base of which wedges 95 apart the nails as desired. The usual heel 100 nails are not springy and retain their bent position. A flat guide plate or die may now be laid inside the group of nail tops and the heel laid against the shoe, and the nails 105 then driven and clenched interiorly, leaving the slightly projecting and parallel nail tops, upon which subsequently the top lift is forced or driven, usually after an application of cement beneath the top lift.

105 Preferably the compressing, the piercing, the inserting of the nails, the partial driving of them, and their bending into parallelism are performed in a single machine, and herein is disclosed and claimed a machine 110

which performs each of, and co-operates in all of, these operations. After such operations the heel is preferably removed and joined with the shoe and the top lift, either 5 by ordinary appliances, or by a special apparatus which I have designed, but which forms no part of the machine herein claimed.

The preferred method of preparing and attaching heels to shoes, performed with the 10 assistance of the machine herein described, is not made the subject of claim of invention herein, and the figures of drawings and claims originally filed herein, directed to the same, have been transferred to divisional application filed April 10, 1919, patented June 29, 1920, Number 1,345,023, to which reference is made for fuller disclosure thereof.

Some of the parts and implements referred to in said divisional application and 20 shown herein include the built-up heel 20, the underneath side of which in the compressing operation is concavely shaped to form the heel seat 22. Short depth nail holes are divergently pierced at the top side of the 25 heel by means of a series of awls 24. This operation is fully indicated in the divisional case. Into the pierced holes are inserted nails 25, and after this operation the nails are driven nearly through the heel, but not 30 so far as to emerge at the base, by a first driver 26. During the driving of the diverging nails the space between them is occupied by a tapering guide 27, the effective surface of which is preferably cone-shaped. 35 This incomplete driving operation leaves protruding nail tops 32, which are slanting as in Fig. 9, but are thereafter straightened out into vertical or parallel nail tops, as in Fig. 10. This renders the heel in readiness 40 to be detached from the machine and applied elsewhere to the shoe by suitable driving means, as more fully explained in said divisional case.

Referring now especially to Figures 1 and 45 2, the machine which is of heavy, rigid construction in proportion to the work being done, is formed with a base casting 40, at the center rear of which is a high upright bracket 41 curved around into the form of 50 an overhanging arm 42. At the center front is formed a second upright bracket 43, or, rather, a pair of such brackets spaced apart and formed at their upper ends with bearings 44 between which is mounted the 55 revolvable heel holding and advancing mechanism. The machine at its lower rear part is formed with a bearing 45 for a power or prime shaft 46. This may be rotated at a fairly high speed, having fast and loose 60 pulleys 47, 48 for throwing power on and off. As the machine may be run to operate upon from between six and twelve heels per minute, a slower running main or drive shaft 50 is provided, driven from the power shaft 46 by a reducing gear consisting of a worm 65

49 on the power shaft meshing with a worm wheel 51 on the drive shaft. The latter shaft carries or actuates the several eccentrics, cranks or other connections for operating the heel pressing and shaping mechanism, 70 the piercing mechanism, the nail positioning mechanism, the nail driving mechanism, and the nail straightening mechanism.

I preferably employ a revoluble heel holder capable of carrying four heels so that 75 while the operative is removing a prepared heel and inserting a rough heel at one point, the preceding heel in the series may be simultaneously undergoing a compression, the heel in advance of that the piercing, and the heel in 80 advance of that the nail receiving and driving operations. I have, therefore, provided a four-armed heel holder or carrier 55, which is shown separately in Fig. 3. Each of its four arms 56 carries suitable means for holding or clasping a heel in such way as to permit the described operations. The arms 56 radiate from a central hub 57 mounted on an axle or shaft 58 journaled in the bearings 44 before mentioned. The shaft and hub are 90 shown secured together by a pin 59, see Fig. 3.

As indicated, the four arms of the heel carrier 55 are preferably arranged at right angles, and in normal position one of them projects forwardly where it is accessible to 95 the operative, while another one stands downwardly in position to co-ordinate with the compressing mechanism; a third one extends rearward where the piercing mechanism operates; and a fourth projects upwardly from the hub, holding the heel where it may receive the nails. One rotation of the main shaft 50 causes one operation of all of the mechanisms, this occupying several seconds of time, but for each heel the complete 100 cycle involves four shifting movements through the four described positions. The shifting of the carrier 55 may readily be arranged to take place automatically but is also conveniently performed by the operative. 110 For the latter purpose, the carrier shaft 58 is extended through its left bearing 44, as seen in Fig. 2, to where a handle 60 is provided for shifting or throwing the shaft to revolve the carrier between operations. 115 The shaft at its extremity is turned down, as shown at 61, to a small diameter and the handle 60 loosely surrounds the shaft at this point, being held axially in place by a collar 62 at the extremity. The handle is capable 120 of operatively engaging and disengaging the shaft by means of four notches 63 in the latter, and a lock pin 64 on the handle. When the pin stands in a notch, the shaft 125 may be rotated by throwing the handle. On the handle is shown a locking lever 65 pressed outwardly by a spring 66 and having its horizontal portion connected to the lock pin 64. The spring, therefore, tends to lift the lock pin out of the notch of the shaft. 130

The shifting operation may be performed as follows. When the handle 60 is brought to the vertical position shown, its lock pin stands over a notch 63. The operative by 5 now pressing the locking lever causes the pin to enter the notch, whereupon he may pull forwardly the handle and swing it downwardly until the carrier has made a quarter revolution. The exact position to 10 which he is to rotate the carrier may be determined by a stop pin 67 projecting from the left bearing standard 43. The handle may be allowed to remain in this position. The heels and carrier become locked in their 15 positions by the engagement of the various mechanisms with them. The operative's hands are left free to remove the prepared heel and substitute another one while the driving shaft makes a complete rotation, 20 upon which he will again manipulate the handle 60 to advance the series of heels one step.

In detail, the heel carrier at each of its 25 arms may comprise opposite, hollow or concave, shell-like clasping members 70. Internally these are shaped to fit the heels to be acted on, and they may be interchangeable to accommodate different sizes or shapes of heels. The front clasp device is shown 30 open in Figs. 1-3, and the others closed upon heels. Each of the clasp members 70 is shown as provided with a shank 71 extending rearwardly and connected to a swiveled block 72 connected by a pivot stud 73, near 35 the hub, with the carrier arm 56. This mounting permits the opposite clasping shells or members to move toward and from each other. When the heel 20 is placed between the shells, its base comes against an inclined 40 block or rest 74, as best shown in Fig. 3, while an underneath supporting finger 75 assists to hold the heel in position until clasped.

Various means may be employed for forcing the clasp members 70 together, and an 45 advantageous one is that shown in Figs. 1 and 2, consisting of a stationary cam 77 co-operating with opposite cam rollers 78 provided on the clasp members or their shanks. 50 Fig. 2 shows that each cam has a recess or dwell at the front, so that the clasp members are permitted to separate and a heel to be extracted and inserted; while below this 55 position the cams trend toward each other, thus forcibly thrusting the clasp members together, after which a long dwell in the cam maintains the holding pressure on the heel until it is passed around through its several operative relations and back to dis- 60 charging position.

The shell-like members 70, 70 constituting the heel clasping devices, each have a sort of universal motion or adaptability so that when the two are forced together they will, 65 in all cases, firmly grasp and hold the heel.

This result is obtained by the flexible construction of the supporting connections including the shank 71 of each clasp member 70; the shank being flexible permits a sort of universal motion to the member. 70

After a rough heel is put into one of the clasp devices 70 and the latter is swung through 90° to the lowermost position, it is in readiness for the compressing or shaping operation. This action is a vertical squeezing operation on the heel between the rest or block 74 above and a rising flat member 80 beneath. The two members 74 and 80 are in the nature of squeezing dies, and it will be seen in Fig. 3 that the upper press 80 member or rest 74 is convex, so as to give to the heel seat the desired concave form, as more fully explained in said divisional application. 75

The aforesaid compression and shaping 80 of the heel is possible because of the rigid mounting of the upper pressure member 74 and its location directly beneath the carrier shaft 58; and by the solid mounting and the powerful lifting actuation of the lower pressure member 80. 90

The latter member is provided with a downwardly extending shank 81 engaged 95 removably and adjustably in a socket centrally formed in a vertical pressure slide 82 fitted within a vertical slideway 83 in the upper front part of the base 40 of the machine.

In order to give the lower pressure member 80 a rising and pressing movement, at 100 first rapid to bring it to position and then slower and powerful, the ideal connections comprise a toggle consisting of a lower link 85 pivoted to the machine base, and an upper link 86 connecting the lower link and 105 the pressure slide 82. A toggle operating connection or rod 87 may be a simple pitman having a bearing or strap 88 engaging around a crank or eccentric 89 mounted on the main or drive shaft 50. By this arrangement 110 each rotation of the shaft causes the toggle 85, 86 to straighten, thus thrusting the rising pressure member 80 against the flat heel top, compressing and shaping the heel against the opposing pressure member 115 or rest 74.

It should be stated that the several parts and mechanism are shown in Figs. 1 and 2 in their imperative positions, that is, disengaged from the heel. The four-armed 120 heel carrier may be considered as having been supplied with a new heel and rotated to bring the latter into compressing position. The drive shaft 50 does not cease turning, and its continued advance brings the compressing mechanism into operation to compress and thereafter release the heel, thus permitting it to be again revolved a quarter turn to undergo the next or piercing operation at the rear. 125

The actuation for the piercing and other mechanisms to be described, is derived from a second eccentric 91 on the drive shaft 50. This is engaged by a strap or ring 92 and the eccentric rod or pitman 93 extending therefrom is preferably adjustable in length by means of an intermediate section 94 having right and left screw threads. The upper end of the rod 93 is vertically guided by a 10 swinging arm 95 pivoted at 96 to the bracket or standard 41. The upward arm constitutes, with the arm 95, a bell crank by which a horizontal forward and rearward movement is afforded for the actuation of 15 the piercing mechanism next to be described.

The piercing mechanism is shown in left elevation in Fig. 1, in plan view in Fig. 4, and in rear elevation in Fig. 5. There is a series or gang of piercing awls 24 arranged 20 to pierce the heel. Seven of such awls are shown although the number of holes pierced might be greater or less. Preferably these awls operate divergently, and this condition presents a difficulty of structure, mounting 25 and operation which has been advantageously met by the present invention. As seen in Fig. 4, each awl preferably comprises not only its operative piercing portion 24 but a shank portion 100, and the latter is shown 30 as standing at a substantial angle, for example at a right angle to the awl proper so as to give the correct and effective mounting illustrated. Each awl is firmly mounted on a carrier 101 and is removable and inter- 35 changeable, although the adjustment for angle is preferably obtained by adjustment of the carriers 101.

To enable the construction and arrangement of the awls, their carriers, and their 40 fittings and actuating connections to be properly understood, it should be explained at the outset that the top view, Fig. 4, is what the operator would see of the piercing mechanism if he should lean over at the 45 front of the machine and look downwardly in the direction of the arrow 4 in Fig. 1. Fig. 4 shows the heel 20 with its concave seat 22 toward the observer, and at the far side the flat heel top which is to be pierced 50 by the awls 24. Fig. 5, being a rear elevation of the parts shown in Fig. 4, requires Fig. 4 to be looked at from the farther side, and the parts 102, 103, 122, 123, 124, 125 shown in Fig. 4 are omitted from Fig. 5, excepting that 122 and 123 are indicated in 55 dotted lines.

As seen in Fig. 5, the seven awl carriers 101 radiate from a common center with, however, a sufficient space between them to 60 accommodate a rod 102 supporting at its forward end a perforated plate 103 serving as a guide for receiving and positioning the awls.

Considered relatively to the horizontal 65 fore and aft axis of piercing operation, the

several awl carriers are divergently mounted. The rear view shows them converging at their operating point, but as shown in Fig. 4 they are divergently mounted. Thus, each carrier block 101 at 70 its outer edge is provided with a dovetailed enlargement 104, and each of these is mounted and slides directly within a fixed guideway 105. These guideways are farther apart at their front than their rear 75 ends, thus giving the diverging awl motion referred to. Fig. 4 shows the carriers and awls slid rearwardly, and their subsequent forward motion will obviously cause the awls 24, guided by the perforated plate 103, 80 to enter and divergently pierce the desired group of holes around the top of the heel.

Adjustment of the extent of angular divergence is desirable, and for this purpose the guideways 105 for the awl carriers, although stationary, are rendered swingingly adjustable by means of outward extensions 106 which are arc-shaped and engage against the inner sides of correspondingly curved supporting brackets 107. To secure 90 the parts in position, the brackets are shown slotted at 108 through which portions of the extension 106 extend, the same secured by an exterior plate 109 and a threaded nut 110. By loosening the nuts 110, the awl 95 carrier guides may be shifted and thereby changed in angle to give the desired angle to the piercing awls.

Each of the curved supporting brackets 107 which holds a carrier guide is in itself 100 formed or mounted on a base block 111, and these seven base blocks, of which three are shown in Fig. 5, are radially and adjustably arranged on a semicircular, vertical, stationary supporting plate 112 secured 105 at the rear side of the front standards 43, 43, over the base of the machine.

By adjusting the radial base blocks 111 toward and from each other, the spacing of the pierced holes may be varied to suit different sizes of heels. Such adjustment is permitted by reason of undercut recesses at the under sides of the base blocks engaging the dovetailed guides 113 outstanding rearwardly from the face of the vertical supporting plate 112. Any suitable mode of effecting the radial adjustment of the base blocks 111 of the curved carrier guides may be employed, as, for example, a threaded rod 115 partially engaged within the 110 threaded interior of the inner ends of the dovetailed guides 113, and at their outer ends having a pair of collars 116 at each side of a recessed downward projection 117 from the base block. By turning the 115 squared end 118 of the rod 115, the base block is thrust radially inward or outward.

The piercing movement of the awls 24 may be effected by a simple forward thrust, simultaneously, of all of the awl carriers 130

101. As shown in Figs. 4 and 5, each carrier at its rear has an overreaching finger or hook 120, so that, after the piercing, the carriers may be pulled away to retract the awls from the heel. The piercing and retracting movements are shown as performed by means of an actuator 122, shown in top view in Fig. 4 and indicated by dotted lines in Fig. 5. This actuator is of a shape corresponding generally to the heel, so that its somewhat semicircular outer flanged portion 123 engages under the seven hooks 120, while the heel 124 of the actuator presses directly against the several awl carriers 101. By this arrangement, the forward thrust of the actuator will cause all of the awls to divergently penetrate the heel, while a retraction of the actuator retracts the awls. For convenience, the rod 102 carrying the perforated 15 guide plate 103 is centrally mounted in the actuator 122, being held forwardly by a spring 125. By this arrangement, when the piercing action takes place, the spring permits the relative yielding of the rod so 20 that the awls may advance through the perforations of the guide plate 103.

The actuator 122 has a rearwardly extending shank 127 of large diameter mounted in a solid bearing or guideway 128 formed in the rear bracket 41 of the machine. Beyond the rear bracket the shank or slide rod of the actuator is provided with a collar 129, and a powerful spring 130 is interposed between the collar and the frame for thrusting the parts rearwardly. The extreme rear of the actuator shank has fulcrumed to it a link 131 which at its forward end is provided with a stud 132 engaging the upper end of the bell crank arm 97 before referred to. Preferably this arm has an elongated, slotted head 98 to receive the stud 132. By this arrangement, the power connections are capable of thrusting the actuator forward to cause the piercing of the holes, whereas the free play in the slot 98 leaves it to the retracting spring 130 to draw the actuator back to normal position.

In Fig. 1 it will be seen that the eccentric 91 has descended to about its half-way position, bringing the bell crank 95, 97 to the position shown; and the continued rotation will carry the actuator 122 further forward to pierce the nail holes in the heel to the required depth, after which the parts will all be retracted and the heel disengaged to permit its revolution for another quarter turn to a position above the heel carrier shaft.

The nail inserting and driving mechanisms comprise preferably a nail holding means or device adapted to stand directly above the heel, and above that a nail driving means adapted to act on an entire group of nails simultaneously; and the nail holding device is preferably shiftable from driving

position to a removed position for receiving nails, and back again for driving purposes. Referring to Figures 1 and 2, the nail holding device or box 140 is shown swingingly mounted through a hub 141 engaged on a vertical axle or stud 142 projecting downwardly from the overhanging arm 42 of the machine. A collar 143 at the lower end of the stud contains a spring 144 which yieldingly upholds the nail box 140 while permitting the swinging movements. In plan view, the nail box is generally fan-shaped or semi-circular in form, as seen in Fig. 8, to conform generally to the shape of the heel, the straight side or diameter of the semicircle standing forwardly.

In Figs. 1, 1^a and 2, the nail box is shown in its lowermost position contacting upon the heel. For receiving nails, the box may be swung outwardly to the left so that its central or nail receiving portion comes to a convenient location. The nails may be fed automatically, and for this purpose I have shown portions of a nail feeding mechanism. Extending leftward below the overhanging arm 42 of the machine is a bracket 146 having a perforated nail guide member 147, the perforations of which will register directly over the nail recesses in the nail box when swung to the left. Leading downwardly to the nail guide 147 is a series of chutes 148 coming from any suitable feeding mechanism of such nature as to drop a series of nails through the chutes at each operation of the machine.

The nail box having thus received a supply of nails, is to be swung forwardly to bring the nails into driving position. To render these swinging movements automatic, in co-ordination with the other actions of the machine, thus relieving the operative of this work, the following connections from the drive shaft may be employed. The hub 141, about which the nail box swings, is shown as having a helical cam groove 150 engaged by a stud 151 which may be moved upwardly and downwardly to cause rotation of the hub. The stud is shown as having shifted downwardly and the nail box swung forwardly, and beyond this point the groove 150 may extend vertically, forming a dwell. 105 105 110

The stud 151 is carried on a hub 154 which 115
may be moved up and down as follows. The
hub surrounds a rod 159, the upper end of
which is connected by pins 159^a with a guide
rod 155 sliding vertically in the frame arm
42. The lower end of rod 159 has a head 120
159^b; and this is connected by a link 153 with
the pitman 93, which moves up and down,
and so moves all the parts, including rods
159 and 155. A spring 158 surrounding rod
159 tends to hold the hub 154 down on the 125
rod head 159^b. To prevent the hub turning
it is provided with a pin 154^a projecting into
a groove 159^c in the rod 159.

It will be understood that in these figures the nail-box 140 has already swung forward on its pivot to its position above the heel and beneath the driving means 165. This forward swinging of the nail-box and its lowering upon the heel took place during the first part of the descent of the pitman 93, link 153 and connected parts. The hub 154 is capable of sliding relatively upward on the rod 159, the spring yielding to permit this. When the nail-box is in contact upon the heel the further downward movement of the pitman merely compresses the spring leaving the nail-box stationary, while at the same time the rod 155 continues its descent, to operate the nail driving mechanism, as will be described. When the parts return upwardly the hub 154 and the nail-box are held down by the spring until the head 159^b contacts and lifts the hub. Thereafter the continued lifting movement first causes the lifting of the nail-box from the heel and thereafter causes the swinging of the nail-box to a position beneath the nail distributor 147. These two movements are effected by the engagement of the stud 151 in the groove 150. The lower part of the groove is vertical. When the stud has reached the bottom of this vertical portion it presses downwardly and lowers the nail-box hub 141 and the nail box. In doing this the spring 144 is compressed. When the stud again rises the spring lifts the nail-box until its hub 141 comes in contact with the portion 146^a of the distributor bracket 146. This serves as a stop to the rise of the nail-box. Thereafter the continued rise of the stud operating in the inclined part of the groove forces the nail-box to swing outwardly to the left and beneath the distributor. The nail-box by lifting before swinging is able to clear the upper ends of the protruding nail tops.

The nail-box hub 141 is shown as having a horizontal finger 157 which cooperates with an upward finger 154^b extending from the hub 154. These two fingers have inclined contacting faces in the nature of cams such that the lifting of hub 154 tends to initiate or assist the swinging movement of the nail-box. The swinging movement from these fingers does not take effect until the nail-box is fully raised and then the stud 151 acts upon the helical groove 150 and the nail-box is swung as described. To insure that the nail-box will not commence to swing until it has lifted sufficiently to clear the nail tops a guard device is provided as seen in Fig. 1^a. This consists of a roller R cooperating with a rib or guide S acting to compel the nail-box to rise vertically. The roller is mounted on the hub 141 and it runs along in contact with the rib, which is stationary, being secured to the part 143. The roller running along the rear edge of the guide prevents swinging movement until lifted suf-

ficiently to pass off the curved end of the guide.

The upper end of the rod 155 is engaged in a slotted enlargement 160 of a lever 161 pivoted at the rear, and at its forward end connected by a pair of upward links 162 to the upward extremity of the nail driving plunger 163, the latter having its sliding bearing in the enlarged forward end 164 of the machine arm 42, and carrying below said arm and directly above the heel the nail driving means 165 comprising a gang of drivers, as will be described.

Normally, the nail holding device 140 is slightly higher than the heel, and the nail driving means 165 is slightly higher than the latter, but during the driving action these mechanisms are all brought into the relative position shown in Fig. 6, contacting directly above the heel. In this figure are seen the gang of nail drivers 26 and also the tapered nail guide member 27. The nail guide member 27 is preferably attached to the nail box 140 so that it swings out with the latter when receiving the nails, and swings back into position above the heel. The member 27 as seen in cross-section in Figs. 6, 9 and 10, in top view in Figs. 7 and 8, and in perspective in Fig. 11, comprises a tapered or conical effective surface 168. This is in effect a half cone. Therefrom, the body of the member extends laterally, as at 169, to where a cross-plate or flange 170 is provided. At the top, the member 27 is formed with an edge or ridge 171 rather than a point. The member is shown attached to the nail box 140 by screws 172 passing through holes in the flanges 170.

It will be understood that the nail box 140 is intended to receive and hold and permit the driving of a group of seven nails. For this purpose seven resilient, radial nail holding devices are provided within the nail box. Each of these is preferably multiple, comprising upper, middle and lower slides 110 175, 176 and 177, each backed up at its outer end by a spring 178, and each inclinedly recessed at 179 at its inner or nail receiving end. These resilient slides all converge upon the tapered guide or cone member 27. As seen in Fig. 6, the topmost resilient slide 175 is in each case somewhat enlarged near the center and provided with an enlarged nail recess to assist the receiving and holding of nails dropped into the nail box from the nail feeding mechanism referred to.

In Fig. 6, the nails are not shown but it will be understood that the box 140 swings forwardly at each operation, with a group of seven nails lying against the conical surface of the tapering guide 27. After reaching nailing position, the nail drivers come into play to drive the nails downwardly into the pierced holes and substantially through the heel, the resilient slides 175, 176, 177

yielding in these operations so as to permit the nails and drivers to pass downwardly as required.

The nail driving device 165 comprises a group of drivers 26 arranged to correspond with the positions of the nails beneath, just as the latter are arranged to correspond with the holes previously pierced in the heel. The nail driver plunger or shank 163, shown in Figs. 1, 2 and 6, has a head 182 at its lower end, below which projects a flange 183 perforated at seven points to receive radial slides 184 carrying the drivers 26 at their inner ends. The purpose of this is to permit radial movement of the drivers, which obviously must spread away from each other as they descend, since the nails enter the shoe divergently and both the nails and the drivers are guided in their descent by the diverging sides of the tapered guide 27. A series of springs 185 yieldingly hold the drivers centrally. A series of screw adjustable stops 186 serve to limit the initial inward movement or position of the drivers.

With the described mechanism, it will be understood that after the nail box 140 has come above the heel 20, the driving mechanism 165 descends, and the gang of drivers 26 being forced downwardly engage the tops of the nails and thrust them simultaneously down the sides of the tapered guide 27, into the pierced holes and down nearly to the point of emergence at the base of the heel. The described actuating mechanism co-ordinates these actions and the swinging of the nail box outward to receive a new group of nails and return. After the nails are driven, the upward retraction of the driving devices permits the nail box to be retracted upwardly, and this is performed by the mechanism before described, so that the tapered guide 27 is bodily lifted from the position of Fig. 9 to the position of Fig. 10.

I prefer to employ headless nails having square shanks and slightly tapering, and the several nails may be of different lengths, for example those at the rear of the heel may be longer than those at the front.

It will thus be seen that I have described a shoe heelng method, and also a machine, the same embodying the principles and attaining the purposes of the present invention. Since many matters of arrangement, combination, procedure, order of steps, designs, details and other features may be variously modified without departing from the underlying principles, it is not intended to restrict the invention to such features except in so far as specified in the appended claims.

What is claimed is:

1. A shoe heel preparing machine comprising a revoluble carrier adapted to hold and advance a succession of heels with the heel tops facing outwardly, and a suc-

sion of mechanisms located outside of the carrier, each adapted to operate inwardly against the top sides of the heels, including, at one station, a compressing and shaping member and means for actuating it, and at a subsequent station a piercing mechanism and means for actuating it, and at a subsequent station a mechanism for driving nails into the pierced holes but not entirely through the heel. 75

2. A shoe heel preparing machine comprising a revoluble carrier adapted to hold and advance a succession of heels, the same having a series of heel clasping devices, each consisting of opposed flexibly mounted concave members, and means for closing said clasping devices upon the heels. 80

3. A shoe heel preparing machine comprising a revoluble carrier adapted to hold and advance a succession of heels, the same having a series of heel clasping devices, each consisting of opposed flexibly mounted concave members, and means for closing said clasping devices upon the heels, comprising a stationary cam device brought into action 90 by reason of the advancing movement of the heel carrier.

4. A shoe heel preparing machine comprising a revoluble carrier having a series of clasping devices closable upon and adapted to hold and advance a succession of pre-assembled heels with the heel tops facing outwardly, exterior compressing mechanism acting radially inwards against the top of each heel to shape and compress it towards 100 the axis of the carrier as the latter pauses in one position, and exterior mechanism for operating against the top of the compressed heel at a subsequent carrier position. 95

5. A shoe heel preparing machine comprising a revoluble carrier adapted to hold and advance a succession of heels with the heel tops facing outwardly, exterior compressing mechanism acting radially inwards against the top of each heel to shape and compress it towards the axis of the carrier as the latter pauses in one position, exterior piercing mechanism operating inwards upon the heel at a subsequent carrier position, and exterior nail-driving mechanism operating 110 inwards upon the heel at a third carrier position. 105

6. A shoe heel preparing machine comprising a revoluble carrier adapted to hold and advance a succession of heels with the heel tops facing outwardly, exterior piercing mechanism operating inwards upon the heel at one carrier position to form diverging nail holes, and exterior nail-driving mechanism operating inwards upon the heel 115 at a subsequent carrier position to divergently drive nails into such holes. 120

7. A shoe heel piercing mechanism comprising a gang of awls, a series of separate sliding awl carriers, separate and adjustable 130

slideways for the respective carriers, and means for actuating all the carriers in one operation.

8. A shoe heel piercing mechanism comprising a gang of awls, a series of separate awl carriers, separate guide means for the carriers, and means for actuating all the carriers in one operation, each of said awls comprising a longitudinal piercing portion, and 10 a laterally extending shank mounted rigidly on its carrier.

9. A shoe heel piercing mechanism comprising a gang of awls, a series of separate awl carriers, separate guide means for the carriers adjustable as to angle of action, and means for actuating all the carriers in one operation.

10. A shoe heel piercing mechanism, comprising a series of separate awl carriers 20 mounted to move in diverging paths, means for adjusting the path or angle of guidance, and a single actuating means for all the carriers.

11. A shoe heel piercing mechanism comprising a gang of awl carriers slidingly mounted in non-parallel ways, means for relatively adjusting the angles of the several ways, awls on said carriers, the longitudinal axis of each awl lying in its path of 30 movement, and a common actuator for said carriers.

12. A shoe heel piercing mechanism comprising a gang of awls, a series of separate awl carriers, separate guide means for the carriers, adjustable both as to angle of action and toward and from each other, and means for actuating all the carriers in one operation.

13. A shoe heel piercing mechanism comprising a gang of awl carriers slidingly mounted in non-parallel ways, means for relatively adjusting the ways to alter the spacing of the carriers, awls on said carriers, the longitudinal axis of each awl lying in its 45 path of movement, and a common actuator for said carriers.

14. A shoe heel piercing mechanism including rotary heel holding means for bringing successive heels to piercing position, a 50 plurality of slidably mounted separate carriers for awls, an actuator for advancing all of the carriers toward each heel, and an awl guide plate yieldingly mounted to advance with the actuator, to contact each heel 55 top in advance of the piercing action.

15. A shoe heel piercing mechanism including heel holding means, a plurality of carriers for awls, an actuator for advancing the carriers toward the heel, and an awl 60 guide plate yieldingly mounted to advance with the actuator, to contact the heel top in advance of the piercing action, said guide plate having a shank extending between the carriers to its yielding mounting on the 65 actuator.

16. A shoe heel preparing machine comprising a shifting carrier adapted to hold and advance a succession of heels to the mechanisms operating thereon, a piercing mechanism operating in one heel carrier position adapted to pierce diverging holes in each heel, and a nail-driving mechanism operating in a subsequent heel carrier position adapted to divergently drive mails into the pierced holes. 75

17. A shoe heel preparing machine comprising a shifting carrier adapted to hold and advance a succession of heels to the mechanisms operating thereon, a piercing mechanism operating in one heel carrier position adapted to pierce diverging holes in each heel, the same having a gang of awls, a series of separate awl-carriers, and divergently arranged guides for the carriers, actuating means for the awl carriers, and a 80 nail-driving mechanism operating in a subsequent heel carrier position adapted to divergently drive mails into the pierced holes, the same having a gang of drivers, a tapered guide for the drivers, nail positioning means, 85 and actuating means for the drivers.

18. A shoe heel nailing machine comprising a heel holding means, a device for holding a group of nails in position to be driven into the heel, the same having a central 95 tapered guide, means for holding nails adjacent the guide, and means for driving such nails.

19. A shoe heel nailing machine comprising a heel holding means, a device for holding a group of nails in position to be driven into the heel, the same having a central tapered guide, means for holding nails adjacent the guide, consisting of a plurality 100 of yielding members for each nail, and 105 means for driving such nails.

20. A shoe heel nailing machine comprising a heel holding means, a device for holding a group of nails in position to be driven into the heel, the same having a central 110 tapered guide, means for holding nails adjacent the guide, consisting of a plurality of yielding members for each nail, and means for driving such nails, consisting of separate 115 yieldable drivers, adapted to advance along said tapered guide, and to displace said yielding members as the nails are driven.

21. A shoe heel nailing machine, comprising a heel holding means, a tapered guide adjacent the heel top, means for moving 120 said guide toward the heel before driving, means for divergently driving a group of nails guided by said guide, and means for withdrawing said guide to spread the converging nail tops. 125

22. A shoe heel nailing machine comprising in combination, means for holding a heel, a tapered nail guide, means for holding said guide against the heel during the driving of the nails, mechanism for driving 130

the nails as guided by said tapered guide, so as to leave the nail ends protruding, and means for retracting said tapered guide for spreading or straightening such nail ends.

- 5 23. In a machine of the kind described, a revolute heel carrier having heel clasps at spaced peripheral points and mounted to revolve about a transverse horizontal axis, a self-acting means to close each clasp before reaching compressing position, compressing mechanism located beneath the carrier axis and operating by upward thrust against the heel toward the carrier axis to compress and shape the heel, piercing mechanism located to the rear of the carrier and operating toward the carrier axis, a nail driving mechanism located above and acting downwardly toward the carrier axis, a nail positioner 35 shiftable laterally between driving and nail receiving positions, means for guiding nails to place in said positioner, and power actuatable drive means, having timed connections to said compressing, piercing, positioning 40 and driving mechanisms.
- 10 24. In a machine of the kind described, a

revolute heel carrier having heel clasps at spaced peripheral points and mounted to revolve about a transverse horizontal axis, a 25 self-acting means to close each clasp before reaching compressing position, compressing mechanism located beneath the carrier axis and operating by upward thrust against the heel toward the carrier axis to compress and shape the heel, piercing mechanism located to the rear of the carrier and operating toward the carrier axis, a nail driving mechanism located above and acting downwardly toward the carrier axis, a nail positioner 35 shiftable laterally between driving and nail receiving positions, means for guiding nails to place in said positioner, and power actuatable drive means, having timed connections to said compressing, piercing, positioning 40 and driving mechanisms.

In testimony whereof, I have affixed my signature hereto.

ANGELO PERRI.
